UNITED STATES PATENT OFFICE.

ALEXANDER MACDOUGALL, OF BAKER, OREGON.

ADJUSTABLE SUPPORTING MEANS FOR DISPLAY CONTAINERS.

Application filed February 27, 1926. Serial No. 91,176.

The present invention relates to a device for raising articles in a display container as such articles are sold and removed from the container in order that the articles remaining may present a better appearance than if left at the lower portion of the container. For example, when cigars are sold from the ordinary display cigar box, after one or more layers of the cigars have been sold, the remaining cigars are not as attractive to the prospective purchaser and very frequently a sale is accordingly lost or a new box of cigars must be opened. Similarly, with other vendible articles, such as chewing gum, the packages remaining after a part of the box has been sold do not present as an attractive appearance as they should. The same difficulty is experienced with articles not disposed in layers, particularly, but indiscriminately piled on one another, and as they are sold the articles remaining are not as tempting to the prospective purchaser.

The device constituting an embodiment of this invention overcomes the difficulties as above set forth and also enables a saving in the number of cartons for larger or deeper cartons may be used since the articles may be raised to a position at or near the top of the container as may be desired. Other advantages of the construction provided will be apparent.

For a complete understanding of the invention, reference is to be had to the following description and the accompanying drawing forming a part of this specification.

In the drawings:—

Fig. 1 is a plan view of a box of cigars having the device of the present invention positioned below the lowest layer of the cigars;

Fig. 2 is a sectional view on the line 2—2 of Fig. 1;

Fig. 3 is a view similar to Fig. 2 showing the articles raised;

Figs. 4 and 5 are similar views showing how the remaining articles may be raised after the articles previously thereabove have been taken from the container;

Fig. 6 is a perspective view of the device looking at the bottom side thereof; and

Fig. 7 is a fragmentary view similar to Fig. 6 but shows a modification; Fig. 8 is a view on the line 8—8 of Fig. 6.

Referring to the drawings in detail, the reference character 10 designates a display

box or container, and while cigars are illustrated, it will be understood that this box may contain any articles. Layers of cigars or other articles are usually packed in such a box 10, these layers being designated by the numeral 11 on the drawing. It will be understood, however, that the invention is likewise adapted for containers in which the articles are not disposed in layers.

Within the box 10 and below the articles therein, is positioned the adjustable bottom or follower 12, shown in perspective inverted position by Fig. 6. This follower device 12 has at the sides thereof a plurality of U-shaped members 13, 14 and 15 supported in bearings 16 and 17. These bearings comprise a corrugated portion 18, the U-shaped members 13, 14 and 15 being received between corrugations, and end extensions 19 which pass through the follower from the bottom side thereof to the top, as shown by Fig. 8, for securing the bearings in place. The follower 12 may be made of any suitable material, such as wood or card-board or the like and may be comparatively thin so as not to increase the size of the container unnecessarily. The bearing members 16 and 17 may be of any suitable material, preferably metal. The U-shaped members 13, 14 and 15, are also preferably of metal. It will be understood that the supporting U-shaped members are rather loosely disposed within the bearings 16 and 17 so that as the follower is raised from the bottom of the container 10, the end portions of the members 13, 14 and 15 tend to assume a vertical position.

It will also be understood that the end portions 13^a, 14^a, and 15^a of these supporting members 13, 14 and 15, respectively, are of graduated length so that as the follower 12 is raised, the end portions will successively function as supports for the follower. The ends of the supporting members may be pointed as is obvious. Any suitable means such as ribbons 20 at the ends of the follower may be provided for raising the latter when desired.

In Fig. 7, there is illustrated a modification of the device. This modification comprises a device most of the parts of which are substantially the same as that shown by Fig. 6, but in order to permit of the application of the supporting members 13, 14 and 15 to a follower member 12 made of material that may be considerably thinner than the follower 12 in the device shown by Fig. 6,

bearing members 21 may be provided, and it will be understood that there is such a bearing 21 at each end of the follower 12. Such bearings 21 comprise the longitudinally extending corrugated portion 22 and the laterally extending securing portions 23 which pass through openings in the follower 12 and secure the bearing member 21 in a manner similar to that illustrated by Fig. 8. It will be understood that these members 21 are combined bearings and reinforcing members.

The construction, operation, and utility of the invention will be apparent from the foregoing description. Figs. 2 to 5 illustrate the manner of operation or use. Fig. 2, shows a new box of cigars, and of course is illustrative of any other articles whether in layers or not, the follower 12 being ineffective at the bottom of the container 10. Fig. 3 shows the follower raised to lift the articles to or near the top of the container, the supporting members 15^a being in position to support the follower 12 in its raised position. Fig. 4 is similar to Fig. 3 but shows the position of the follower 12 when more articles have been removed from the container although the remaining articles are thereby positioned at or near the top and present the appearance of being in a newly opened box. In this latter view, the supporting members 14^a are in effective position to support the follower 12. Fig. 5 shows the position of the parts when the container is, perhaps, almost empty, and yet the articles are at or near the top and present the inviting appearance that a newly opened box presents. In this latter position, the longer end portions are effective to support the follower 12 as indicated at 13^a in this view.

It will be understood that the device illustrated by Fig. 7 may be operated in the same way as that shown by Fig. 6 and may assume the positions illustrated by Figs. 2 to 5.

While the preferred embodiment of the invention has been described and shown by the

drawing, it will be understood that certain changes in the construction and arrangement of parts may be made and will suggest themselves in view of this disclosure, but all such changes are to be considered as part of the present invention as defined by the appended claims. It will also be understood that while advantages have been specifically described, other advantages will be incidental to the use of the device embodying the present invention.

Having thus described the invention, what is claimed and desired to be secured by Letters Patent of the United States is:

1. In combination with a container for articles sold therefrom, a device for lifting such articles toward the top of the container, comprising a follower member positioned within the container below the articles therein, corrugated bearing members secured to said follower at the ends thereof, and a plurality of graduated U-shaped supporting members loosely mounted in said bearings having their intermediate portions extending across said follower whereby to reinforce it, and their free ends extending below said follower whereby to successively engage the bottom of the container as said follower is raised.

2. In combination with a container for articles sold therefrom, a device for lifting such articles toward the top of the container, comprising a follower member positioned within said container below the articles therein, corrugated bearing members secured to said follower at the ends thereof and extending thereacross to reinforce the latter, and a plurality of graduated U-shaped members having their intermediate portions loosely mounted in said corrugated bearing members and their free ends extending below said follower whereby to successively engage the bottom of the container as said follower is raised.

In testimony whereof, I hereunto affix my signature.

ALEXANDER MACDOUGALL.
